TWIN BED STRUCTURE

Nicola Iaquinta, Montebello, Calif., assignor to The Inc. Company, Los Angeles, Calif., a copartnership

Application March 12, 1956, Serial No. 570,834

2 Claims. (Cl. 5—2)

This invention relates to a twin bed construction, and more particularly to a structure in which two beds or couches may be pivotally joined together on a vertical axis, either adjacent the head or foot portion of the bed or couch.

It has been known in the past to provide such a structure. However, the beds or couches were permanently joined by a pivot in such manner that they were confined to relative angular movement. Usually casters or rollers are joined to the bed frame to facilitate this angular motion.

It is one of the objects of this invention to provide a structure of this character that makes it possible to separate the beds in a convenient manner so that the beds may be moved into any desired position.

This invention posses many other advantages, and has other objects which may be made more clearly apparent from a consideration of several embodiments of the invention. For this purpose, there are shown a few forms in the drawings accompanying and forming part of the present specification. These forms will now be described in detail, illustrating the general principles of the invention; but it is to be understood that this detailed description is not to be taken in a limiting sense, since the scope of the invention is best defined by the appended claims.

Referring to the drawings:

Figure 1 is a pictorial view of a pair of beds or couches utilized in accordance with the invention;

Fig. 2 is an enlarged sectional view, taken along a plane corresponding to line 2—2 of Fig. 1;

Fig. 3 is an enlarged sectional view, taken along a plane corresponding to line 3—3 of Fig. 1;

Fig. 4 is a view similar to Fig. 2, illustrating the manner in which the head or footboards can be separated; and

Fig. 5 is a pictorial view of the standard utilized in connection with the invention.

The beds or couches 1 and 2 may be supported on rollers or casters (not shown). Each of these may be provided with a board 3 or 4 corresponding either to the head or footboard.

In order to join the boards 3 and 4 pivotally, use is made of a hinged construction having leaves 5 and 6 fastened respectively adjacent the vertical edges of the boards 3 and 4. These leaves have interleaving lugs 7, and a removable hinge pin 8 joins these lugs pivotally together. 60

2

Due to this construction, the devices 1 and 2 can be angularly moved with respect to each other. They may be entirely separated by moving the hinge pin upwardly by the aid of a handle 9. When so removed, the two beds or couches 1 and 2 may be placed in any desired position in the room.

It is often desirable to provide a table 10 adjacent the boards 3 and 4 so that the boards fall vertically along adjacent sides of the table. For this purpose, the lower 10 end of the hinge pin 8 is adapted to be supported in a socket 11 joined to a standard 12 (Fig. 5). This standard serves to accommodate a leg 13 of the table 10. This leg is shown in the present instance as made of angle iron. It is located in a triangular-shaped socket 14. The 15 socket 14 is formed by the aid of an angle iron 15 having flanges welded to the socket 11, as well as to the base member 12. This member has a horizontal flange extending under socket 14, as well as a vertical flange co-operating with the pair of flanges of member 15 to form 20 the socket 14. The table 10 may be readily removed, if desired, by lifting the leg 13 out of the socket 14. Furthermore, if convenient, the base 12 may be permanently attached to the floor of the room so as to locate permanently the vertical pivot about which the 25 beds or couches 1 and 2 may be angularly adjusted.

It is a simple matter to remove the pin 8 and to roll the beds 1 and 2 to the desired position. Furthermore, by moving the beds or couches 1 and 2 so that the lugs 7 overlie the socket 11, the hinge pin 8 may be used to 30 join the beds together along a vertical axis. In the position shown in Fig. 1, the beds 1 and 2 may be so arranged that the beds lie longitudinally adjacent the walls of a room. The table 10 may then occupy a position in the corner of the room.

35 The inventor claims:

1. In a structure of the character described: a pair of couches, each couch having a head end and a foot end; a single pivotal connection between the couches, the pivot axis of the connection being vertical and arranged between adjacent sides of the couches and near one end of each couch; said pivotal connection including a hinge element at an end of each said couch cooperating with a fixed standard having a first socket, and a single removable hinge pin pivotally uniting said elements and socket; and said standard having a second socket adjacent said first socket for receiving the lower end of a table leg.
2. In a structure as set forth in claim 1, said standard further including an angle piece having a horizontal flange and a vertical flange, said horizontal flange forming a base for said sockets, and said second socket being formed by a pair of flanges cooperating with said vertical flange.
